United States Patent Office

Des. 193,273
Patented July 24, 1962

193,273

PLAYGROUND DEVICE

William T. Kennedy, Jr., Belleville, and Wayne Haubert,
Mifflintown, Pa., assignors to The Mexico Forge, Inc.,
Mexico, Pa., a corporation of Pennsylvania

Filed June 28, 1961, Ser. No. 65,744

Term of patent 14 years

(Cl. D34—5)

FIG. 1 is a perspective, side view of a playground device showing our new design; and

FIG. 2 is a top view of said device with the broken line portions seen in FIG. 1 omitted for convenience of illustration.

The essential features of the design are shown in full lines.

We claim:

The ornamental design for a playground device, substantially as shown and described.
